UNITED STATES PATENT OFFICE

2,415,372

SWEEPER

Lloyd B. Salt, Newton, and Corradino R. Zaimo,
Hyde Park, Mass., assignors to B. F. Sturtevant
Company, Hyde Park, Mass.

Application June 16, 1945, Serial No. 599,852

3 Claims. (Cl. 15—43)

1

This invention relates to sweepers having motor driven brushes.

It is generally recognized that for cleaning a rug well, the suction of the usual vacuum sweeper is insufficient since it will not pick up hairs and threads which have become intertwined upon the rug surface, and it has been customary to use brushes or beaters having axes parallel to the rug surface, in the sweeper nozzles. Such devices have added to the weight and complications of already heavy and complicated vacuum sweepers and have not been entirely satisfactory for that reason.

Another disadvantage of the usual vacuum sweeper is that it has an external dust receiving bag which is unsightly, and which adds to the bulk and inconvenience of the sweeper.

This invention provides a small, inexpensive and easily handled sweeper which does not have a suction nozzle, and which has brushes rotating in a plane parallel to a rug surface for dislodging dust and other particles and for throwing same by centrifugal force into an annular collection chamber included in the sweeper housing.

A feature of the invention resides in the provision of the annular collection chamber above and around the rotary brushes, the chamber having a tangential incline over the upper surface of which the dust and other particles are moved by the action of the brushes.

Another feature of the invention resides in combining with the brush structure, a centrifugal fan which acts to draw air over the sweeper motor for cooling same, and which discharges the drawn in air into the dust stream entering the collection chamber.

Another feature of the invention resides in providing the sweeper with a removable cover which forms the cover for the dust chamber whereby upon removal of the cover, the sweeper can be turned over for discharging the contents of the dust collection chamber as by dumping the sweepings upon a paper spread upon the floor.

Objects of the invention are to reduce the size, weight and cost of sweepers, and to improve their appearance and ease of handling.

The invention will now be described with reference to the drawings of which:

Fig. 1 is a side elevation, with a portion in dashed outline, of a sweeper embodying this invention;

Fig. 2 is a plan view looking downwardly upon the sweeper of Fig. 1;

Fig. 3 is an enlarged sectional view along the lines 3—3 of Fig. 2;

2

Fig. 4 is a sectional view along the lines 4—4 of Fig. 3;

Fig. 5 is an enlarged view of the entrance to the dust collection chamber of the sweeper, and

Fig. 6 is a plan view of the top of the brush supporting disc of the sweeper, and illustrates the fan blades thereon.

The electric motor 10 has a shaft 11, to the lower end of which is attached the brush supporting disc 12. The brush holders 13 are supported in the radial slots 14 in the disc 12, and have portions extending above the upper surface of the disc and which act as fan blades. The blade members 15 which are similar to the upper portions of the brush holders 13, are attached radially to the upper surface of the disc 12, and provide with the upper portions of the holders 13, equally spaced fan blades, the disc 12 forming the back plate for the blades. The brushes 16 extend downwardly from the holders 13, through the central opening 17 in the lower wall 18 of the sweeper housing.

The partition 19 extends from the base of the motor 10 to the cylindrical side wall 20 of the 25 sweeper housing, and forms the floor of the dust collection chamber 21. The cylindrical inner wall 22 which extends vertically above the motor base, forms the inner wall of the chamber 21. The partition 19 has a portion 23 which extends downwardly to the opening 17, and which serves as a tangentially arranged incline for conveying the particles thrown off by centrifugal force by the brushes 16, into the chamber 21.

The cylindrical side wall 20 of the sweeper has 35 the vertically arranged, spaced perforations 24 as illustrated by Figs. 1 and 5. The porous member 25 of cloth or other suitable material, extends around the chamber 21, against the inner surface of the wall 20, and provides with the perforations 24, passage from the sweeper of the air entering the chamber 21, but prevents the passage of dust therefrom.

The upper ends of the walls 20 and 22 have the rubber tubular members 26 thereon and upon which the sweeper cover 27 rests, it being retained in position by the hinged clamps 28. The cover 27 has the handle retaining portion 29 to which the handle 30 is pivoted and through which the motor lead wires 31 extend.

The lower surface of the cover 27 has the conventional female, electric plug receptacle 32 attached thereto, and which is plugged onto the male plug 33 on the upper end of the motor 10. The electric energizing circuit of the motor is completed through the wires 31 and the recep-

tacle 32 and plug 33 when the cover 21 is clamped into position as illustrated by Fig. 3. When the cover is removed the receptacle 32 is removed from the plug 33, and the motor circuit is broken.

The sweeper cover 21 has the holes 35 therein around the upper end of the motor 10. The motor base has the holes 36 therein around the lower end of the motor.

The circular plate 37 is attached to the partition 19 and extends below the motor base, and has the central opening 39 above the brush supporting disc 12.

The fan blades 13 and 15 upon rotation of the disc 12, move air through the holes 35 in the sweeper cover 21, over the surface of the motor, and through the holes 36 and opening 39, and blow the air into the collection chamber 21. The air so moved cools the motor 10, and aids somewhat in the movement of dust into the chamber 21.

In operation, upon rotation of the disc 12, and the movement of the sweeper over a rug surface, the brushes 16 dislodge dust and other particles from the surface, and throw the particles outwardly by centrifugal force, the particles being forced up the incline formed by the partition portion 23, into the chamber 21. The partition 40 extending between the walls 20 and 22 stops the whirling motion of the sweepings and causes them to build up in depth in the chamber 21, as the sweeping progresses. At the same time, the blades 13 and 15 draw air over the surface of the motor and discharge the air into the dust stream entering the chamber 21.

While one embodiment of the invention has been described for the purpose of illustration, it should be understood that the invention is not limited to the exact apparatus and arrangement of apparatus illustrated, as modifications thereof may be suggested by those skilled in the art without departure from the essence of the invention.

What is claimed is:

1. A sweeper comprising a housing having an outer and a lower wall, said lower wall having an inner, circular opening therein, a motor supported in said housing above said opening, said motor having a shaft extending downwardly along the axis of said opening, brush supporting means attached to said shaft, brushes extending downwardly from said supporting means into said opening, a partition extending around said motor and spaced from said outer wall, said partition and said outer wall forming therebetween a dust collection chamber, a second partition extending between said outer wall and said partition above said lower wall and forming the floor of said chamber, said second partition having a portion extending downwardly to said lower wall and forming an incline for the passage into said chamber of particles swept up by said brushes and thrown out therefrom by centrifugal force, and a removable cover for said sweeper, said cover extending over said chamber.

2. A sweeper according to claim 1 in which

said outer wall and said first mentioned partition are formed substantially as coaxial cylinders, and said portion of said second partition extends in a circular arc between said outer wall and said first mentioned partition.

3. A sweeper comprising a housing having an outer and a lower wall, said lower wall having an inner, circular opening therein, a motor supported in said housing above said opening, said motor having a shaft extending downwardly along the axis of said opening, a brush supporting disc attached to said shaft, brushes extending downwardly from said disc into said opening, a partition extending around said motor and spaced from said outer wall, said partition and said outer wall forming therebetween a dust collection chamber, a second partition extending between said partition and said outer wall above said lower wall and forming the floor of said chamber, said second partition having a portion extending downwardly to said lower wall and forming an incline for the passage into said chamber of particles swept up by said brushes and thrown out therefrom by centrifugal force, a removable cover for said sweeper, said cover extending over said chamber, means forming spaced, radially extending fan blades on the upper surface of said disc, a plate extending over said blades, said plate having an opening around said shaft for admitting air into the inner ends of said blades, said cover having openings therein above said motor, and means including said openings in said cover and including said opening in said plate for passing air from the exterior of said sweeper over the surface of said motor and into said blades, the air discharged by said blades passing with the particles thrown out by said brushes, into said chamber.
